COMBINED DIODE DETECTOR AND
AMPLIFIER CIRCUITDon G. Burnside, East Orange, N. J., assignor to
Radio Corporation of America, a corporation of
Delaware

Application September 27, 1933, Serial No. 691,115

9 Claims. (Cl. 250—27)

My present invention relates to radio receivers, and more particularly to receivers utilizing tubes adapted to simultaneously perform diode detection, audio amplification and automatic volume control functions.

There has been disclosed by T. M. Shrader, in application Serial No. 622,140, filed July 12th, 1932, radio receiver circuits employing multi-function tubes adapted to perform diode detection, audio amplification and automatic volume control. Such tubes are designated as "55" tubes, and utilize independent diode detector and amplifier sections. The essential feature of the tube construction involves the disposition of the diode anode, or anodes, adjacent a portion of the cathode, this portion supplying electrons solely to the diode anode. It will, therefore, be seen that the full cathode surface in the 55 tube is not utilized to feed electrons to the amplifier section.

Accordingly, it may be stated that it is one of the important objects of this invention to provide a signal receiving system wherein a multi-function tube is employed for simultaneous diode detection, audio amplification and automatic volume control, the tube being especially characterized by the inclusion within the tube envelope of a diode anode which employs the electron stream supplied to the amplifier section of the tube, the said diode anode nevertheless drawing only a portion of the electron stream.

The aforementioned 55 tube has revealed an undesirable characteristic in actual operation. When such a tube is employed in a multi-function network of the type disclosed in the aforementioned Shrader application, it is found that an appreciable bias voltage is developed across the diode load when no signal is applied to the diode. The development of this bias voltage is due to the effect of contact potential and/or initial electron velocities.

Accordingly, it is pointed out that it is another important object of the present invention to secure simultaneous diode detection, audio amplification and automatic volume control in a network employing a single tube, the diode section of the tube being so constructed that the effect of contact potential and/or initial electron velocities is much less than when using a 55 tube, resulting in but little, or no bias voltage being developed across the diode load when no signal is applied to the network.

Still another important object of this invention is to provide in a receiver a tube which utilizes a filament heating current of 2 volts, and that can be efficiently used as a combined detector, audio amplifier and automatic volume control tube.

And still another object of this invention is to provide a combined diode detection, audio ampli-

fication and automatic volume control network which utilizes a tube of the type having a cathode, an anode, and five interposed grid electrodes, the grid second from the cathode drawing only a portion of the electron stream and functioning as a diode detector anode. 5

Still other objects of the invention are to improve generally the simplicity and efficiency of receivers employing multi-function tubes, and to particularly provide a receiver of this type which is not only reliable in operation, but economically manufactured and assembled. 10

The novel features which I believe to be characteristic of my invention are set forth in particularity in the appended claims, the invention itself, however, as to both its organization and method of operation will best be understood by reference to the following description taken in connection with the drawing in which I have indicated diagrammatically several circuit organizations whereby my invention may be carried 15 into effect. 20

In the drawing:—

Figure 1 diagrammatically shows a radio receiver of the superheterodyne type embodying 25 the present invention.

Figure 2 shows a modified form of the multi-function network.

Referring now to the accompanying drawing, wherein like reference characters in the two figures represent similar circuit elements, there is shown in Figure 1 a conventional type of superheterodyne receiver. The source of signals, which is conventionally represented, may be the usual grounded antenna circuit, the signal collector device of an automobile receiver, or any other desired signal collection means. The signal collector is shown feeding the collected signals, which signals preferably are in the broadcast frequency range, to a combined detector-oscillator network. This network, represented by the numeral 1, is not shown in its structural details for the reason that those skilled in the art are well acquainted with such details. 30 35 40

As a specific example of the combined detector-oscillator network, reference is made to the arrangement shown in Haines application Serial No. 663,171, filed March 28th, 1933. The arrangement shown in this Haines application employs a tube known as a "2A7" tube. The 45 tube is also known as a pentagrid converter, and consists, in addition to the cathode and plate, of five grids disposed between the cathode and plate. Of course, any other well known type of detector-oscillator network may be employed in 50 55 the network 1.

The intermediate frequency output of the network 1 is fed to the intermediate frequency amplifier network 2, and the amplified intermediate frequency energy is then transmitted through 60

the tuned coupling **M**₁ to the multi-function tube **3**. The latter is of the type known as "1A6", and includes a filament **4** that operates with 2 volts and a current of 0.06 ampere. The tube also includes an anode **5'**, and five grids between the filament **4** and the anode **5'**. The actual construction of tube **3** may follow the construction shown for the "2A7" tube in the aforementioned Haines application. Briefly, in such a tube the grids are interposed between the cathode and plate so as to be passed in succession by the electron stream from the cathode to the plate, and are preferably arranged coaxially with the cathode. The grids are the usual wound grids, each consisting of two parallel grid rods and a helix of cylindrical grid wire with its turns fastened to the grid rods. The grid immediately adjacent the filament **4** is designated by the numeral **5**. The next grid, designated by the numeral **6**, is the diode anode, and is constructed to draw only a fraction of the electron stream. The electrode **6** preferably has no grid wire helix, but is merely two grid rods mounted in alignment with the grid rods of the remaining grids. The conventional representation of the electrode **6** is to be understood as covering the aforementioned construction, or any other construction wherein the diode anode **6** is made to draw only a portion of the electron stream, while being in the path of the electron stream from the filament **4** to the remaining grids and the anode **5'**.

The grid **7** and the grid **8** are electrically connected together, and between them is disposed the grid **9**, which functions as the audio signal grid. The diode detector circuit includes the electrode **6**, the signal input circuit **10**, the resistor **R**₁, the latter being shunted by the radio frequency by-pass condenser **11**, and the connection to the electrical center of the filament resistor **R**₂. The audio frequency signal potential developed across resistor **R**₁ is fed to the audio grid **9** through a path which includes the condenser **12** and the lead **13**, it being noted that one side of the condenser **12** is connected to the negative side of resistor **R**₁. The audio grid **9** is maintained at a normal negative bias potential through a path which includes the biasing source **14** and the resistor **15**, and the lead **13**, the source **14** having a potential value of about minus 3 volts. The direct current potential developed across resistor **R**₁ is utilized for automatic volume control of the preceding networks, and the path designated "AVC" is to be understood as representing the automatic volume control arrangement which functions to reduce the gain of the amplifier **2** and the detector-oscillator **1** with increasing signal carrier amplitude. The resistor **16** and grounded condenser **17** provide the usual radio frequency filter circuit employed in the automatic volume control path, the diode detector side of the lead **18** being connected to the negative side of resistor **R**₁.

The audio amplifier section of tube **3** includes, in addition to the grid **9**, the grids **7** and **8**, as well as the anode **5'**. The grids **7** and **8** are connected by a lead **19** to the positive side of a potential source **20**, the potential difference between the grids **7** and **8** and the filament **4** preferably being plus 30 volts. The anode **5'** is connected through the positive side of the potential source **21** to a path which includes the choke **22**, the resistor **23** and the lead **24**. Of course, the sources **20** and **21** can be a common potential source, and in such a case the potential difference between the anode **5'** and the filament **4** is preferably plus 180 volts. The amplified audio frequency signal energy is fed to a succeeding audio frequency load

network, and the latter may comprise further audio amplification networks and/or a reproducer.

The grid **5** is connected to the filament electrical center through a lead **25**. Appropriate by-pass condensers are connected between the grid **5** and the circuit including anode **5'**, and also between the grid **5** and the lead **19** to the positive grids **7**, **8**. It is believed that the operation of the arrangement shown in Figure 1 will be clearly understood from the foregoing description, as well as by virtue of the following explanation.

Heretofore there has not been available a 2 volt tube that could be used as a combined detector, amplifier and automatic volume control tube. The "55" type of tube additionally possesses the undesirable feature of developing bias voltage across the diode load when no signals are impressed on the diode. It has been found, however, that the tube **3** functions in a satisfactory manner when a 2 volt filament heating source is only available. Since the grid **6** has but little effect on the electron stream because of its design, it is used as the diode detector anode. It is particularly useful this way when the grid **5** is tied to the filament **4**. Without going into any theoretical explanation of the operation involved, it is pointed out that the maintenance of the grid **5** at cathode potential results in a substantial suppression of the effect of contact potential and/or initial electron velocities upon the diode anode **6**. At the no-signal condition little or no bias voltage is developed across the diode resistor **R**₁, thus avoiding a reduction in the sensitivity of the controlled amplifiers through the AVC lead. It will, therefore, be seen that the tube **3** embodies a diode section which includes the filament **4**, the suppression grid **5** and the diode anode grid **6**, as well as a tetrode audio amplifier section which includes the filament **4**, the audio signal grid **9**, the grids **7**, **8** functioning as a positive screen grid, and the plate **5'**. The tube not only operates efficiently from a 2 volt heating source in the manner specified, but possesses the additional advantages of permitting the entire cathode surface of the cathode **4** to supply electrons to the tetrode electrodes, and substantially preventing the occurrence of bias voltage across the diode load when no signals are impressed on the diode.

In Figure 2 there is shown a modified method of using the tube **3** in the receiver network. Here the screen grid section of the tube operates as an intermediate frequency amplifier to supply carrier voltage to the diode anode grid **6** through the medium of the tuned transformer **30**. In other words, the tuned input circuit **10**, which is tuned to the intermediate frequency, feeds intermediate frequency energy to the tetrode amplifier which comprises the filament **4**, the signal grid **9**, the screen grids **7**, **8** and the plate **5'**. The amplified intermediate frequency energy is transmitted to the tuned secondary circuit **31** of the transformer **30**, and the diode comprising filament **4**, suppressor grid **5** and the diode anode grid **6** rectifies the intermediate frequency energy. The audio frequency component of the rectified energy which is produced across resistor **R**₁ is fed to the succeeding audio frequency network, while the direct current component is employed for automatic volume control.

It is pointed out that the first grid **5** may be employed as the diode anode in place of the electrode **6**, the grids **7** and **8** functioning to electrostatically shield the audio grid from the carrier on the grid **5**. Used in this manner the rectification efficiency of the diode is relatively higher.

However, such use may be found objectionable in that with a modulated carrier on grid 5 a modulated electron stream is supplied to the tetrode section of the tube. The action of the grid 5 on the electron stream may result in undesirable detection in the tetrode section. It is for this reason that the grid 6 is preferably employed as the diode anode, since it has little effect on the electron stream. It is particularly useful this way when the grid 5 is tied to the filament, even though at the expense of a certain amount of rectification efficiency.

Of course, the tube 3 is not limited in its use to a superheterodyne receiver, since it may be employed with equal efficiency in a receiver of the tuned radio frequency amplifier type. Furthermore, while I have indicated and described several systems for carrying my invention into effect, it will be apparent to one skilled in the art that my invention is by no means limited to the particular organizations shown and described, but that many modifications may be made without departing from the scope of my invention as set forth in the appended claims.

What I claim is:—

1. In combination with a radio frequency amplifier, a multifunction tube including a cathode, two anodes and at least two grids, an input circuit coupled to said amplifier and connecting one of said anodes to said cathode, said input circuit including an impedance and coaxing with said one anode and cathode to provide a diode rectifier, means for connecting one of said grids to a point on said impedance, means for connecting the other anode to said cathode through a path which includes a source of positive anode potential, said point supplying the audio frequency component of the potential developed across said impedance to said one grid, an automatic gain control connection between said impedance and the amplifier, said other grid being disposed between said diode anode and the cathode and being maintained at substantially cathode potential whereby the development of a bias voltage across said impedance is substantially prevented.

2. In an arrangement as defined in claim 1, said diode anode being disposed in the electron stream from said cathode to said two grids and remaining anode, said diode anode being so constructed and arranged as to draw only a portion of said electron stream.

3. In an arrangement as defined in claim 1, at least two additional grids disposed within said tube, the grid having the connection to said impedance being disposed between said two additional grids, and means for maintaining said two additional grids at a positive potential with respect to the cathode.

4. In a radio receiver, a multiple function tube including a filament, a plate, and five grids disposed between the filament and plate, one of said grids being constructed and arranged to draw only a portion of the electron stream from said filament, a signal input circuit including a resistor connected between said one grid and the filament and providing a diode detector circuit, a second one of said grids being disposed between said first grid and said filament and being connected to said filament whereby it is at filament potential, a third one of said grids being connected to a point on said resistor whereby the audio component of rectified signals is fed to said third grid, and the

said third grid being disposed between the remaining two grids, means for maintaining the remaining two grids and said plate at a positive potential with respect to the filament whereby the audio component is amplified in said plate circuit.

5. In a radio receiver as defined in claim 4, means for connecting said filament to a 2 volt heating source, and a direct current automatic volume control connection connected to the negative side of said resistor.

6. In a receiving system, a tube provided with at least a cathode, a positive plate, and an auxiliary electrode disposed in the electron stream between the cathode and plate, the electrode being constructed and arranged to draw only a portion of the stream from the cathode, a signal input circuit including an impedance connected between said cathode and auxiliary electrode and providing a diode rectifier circuit, an automatic gain control connection connected to a point on said impedance, a cold electrode disposed in said stream between said cathode and auxiliary electrode, and said cold electrode being maintained substantially at cathode potential whereby said point is prevented from assuming a substantial negative potential with respect to the cathode when no signals are impressed on said input circuit.

7. In combination, an electron discharge tube provided with a cathode, an anode and a plurality of electrodes interposed between the cathode and anode, a diode rectifier circuit including an impedance connected between the cathode and one of the interposed electrodes, second from the cathode, an automatic gain control connection to a point on said impedance, and a direct electrical connection between the cathode and the electrode next adjacent thereto.

8. In combination, an electron discharge tube provided with a cathode, an anode and a plurality of electrodes interposed between the cathode and anode, a diode rectifier circuit including an impedance connected between the cathode and one of the interposed electrodes, second from the cathode, a source of signal frequency coupled to said rectifier circuit, a path connecting a point on said impedance and another of said interposed electrodes whereby the audio component of rectified signals is impressed thereon, an automatic gain control connection to a point on said impedance, a direct electrical connection between the cathode and the electrode next adjacent thereto, and an output circuit connected between the anode and cathode.

9. In combination, an electron discharge tube provided with a cathode, an anode and a plurality of electrodes interposed between the cathode and anode, a signal input circuit connected between one of said interposed electrodes and the cathode, an output circuit connected between cathode and anode, a diode rectifier circuit coupled to said output circuit including an impedance and connected between the cathode and one of the interposed electrodes, second from the cathode, a path connected to a point on said impedance for deriving an audio frequency component from the rectified signals, an automatic gain control connection to a point on said impedance, and a direct electrical connection between the cathode and the electrode next adjacent thereto.

DON G. BURNSIDE.
